ADVERTISING SIGN

Thomas R. Terry, Idaho Falls, Idaho; Woodrow Galt Terry administrator of Thomas R. Terry, deceased

Application March 8, 1950, Serial No. 8,388

Term of patent 14 years

(Cl. D1—12)

To all whom it may concern:

Be it known that I, Thomas R. Terry, a citizen of the United States, residing at Idaho Falls, in the county of Bonneville and State of Idaho, have invented a new, original, and ornamental Design for Advertising Sign, of which the following is a specification, reference being had to the accompanying drawings, forming part thereof.

I claim:

The ornamental design for an advertising sign, as shown.

THOMAS R. TERRY.
